Inventor
Wm. C. Goldthwait

UNITED STATES PATENT OFFICE.

WARREN GOLDTHWAIT, OF BOSTON, MASSACHUSETTS.

DESIGN FOR TOILET-STANDS.

Specification forming part of Design No. **11,188**, dated May 13, 1879; application filed September 16, 1878.
[Term of patent 7 years.]

To all whom it may concern:

Be it known that I, WARREN GOLDTHWAIT, of Boston, in the county of Suffolk and State of Massachusetts, have invented and produced a new and original Design for a Toilet-Stand, of which the following is a full, clear, and exact description, reference being had to the accompanying photographs, making part of this specification, in which—

Figure 1 is a perspective view of my toilet-stand. Fig. 2 is a perspective view of the same, with the articles which it is intended to hold in place.

In the said photographs, A represents the top of the stand, with a hole, a, for the reception of the wash-bowl B, Fig. 2. Below this top A are the shelves C D, which are connected together and with the top by three strips, b, each of which is bent in the form of a double reverse curve, as shown, and is attached to the outeredges of the top and shelves, the lower portions of the strips beneath the shelf D forming legs c for the stand to rest

on. The lower shelf, D, is of oval form, and is intended for a foot-tub, E, to rest on, and the shelf C above it is elongated, and adapted to support a water-carrier, G, and slop jar or pail, H. At one side of the top is formed an aperture, d, for the reception of a soap-dish, I, and from opposite sides of the top project towel-racks L L.

What I claim as my invention, and desire to secure by Letters Patent, is—

The design for a toilet-stand, consisting of the top A, with its annular openings a d and curved towel-racks L L, the elongated double shelf C, and oval shelf D, and the connecting supporting-strips b, of double-reversed-curve form, terminating in legs c, substantially as herein shown and described.

Witness my hand this 13th day of September, A. D. 1878.

WARREN GOLDTHWAIT.

In presence of—

P. E. TESCHEMACHER,
N. W. STEARNS.
